UNITED STATES PATENT OFFICE

2,324,443

FILLING AND CLOSING MACHINE

Charles T. Walter, Chicago, Ill., assignor to Industrial Patents Corporation, Chicago, Ill., a corporation of Delaware

Application March 5, 1941, Serial No. 381,863

12 Claims.

(Cl. 226—51)

The present invention relates to an automatic type of machine for filling cartons or other similar containers and for effecting a partial closing of an inner liner for the same.

Among the objects of the present invention is to provide a novel device for delivering at proper intervals measured quantities of fluid material to successively presented lined containers, such as fiber cartons and the like, and, at the proper interval of time, successively ejecting said containers with the liner in partially closed condition into a position where an operator may complete the closing operation and discharge the same from the machine.

The invention is predicated upon the idea of constructing an automatic machine of the type herein contemplated of simplified construction, readily and easily assembled at low cost, positive in action, and requiring very little attention in order to maintain its operativeness, but which will, at increased speed as compared to those devices now in use, deliver in a given length of time a greater number of filled cartons to an operator or operators who complete the folding and closing operations on the said containers to produce the finished packaged goods.

A further object within the purview of the invention is to provide a novel combination of means for feeding the containers into position for receiving the fluid material and the ejecting and closing means to facilitate the packaging of the material whereby increased productive capacity is assured when compared with ordinary filling machine equipment now in use.

Still another object of the present invention is to provide a novel arrangement of the various control mechanisms for the fluid feeding and measuring means and the ejector and closing mechanisms which provides for positive and controllable operation thereof under all circumstances for the proper delivery of the fluid material to the containers, the ejection of the filled containers from their material receiving position, and the partial closing of the inner liner thereof when received in the immediate vicinity of the operator, thus facilitating the final closing operation and the discharge thereof from the machine by the operator.

A further object of the present invention is to provide a novel combined fluid delivery mechanism and anti-drip device, both of which are controlled by the control mechanism for the proper sequential operation of the anti-drip device toward the end of the delivery cycle to prevent dripping of the fluid material over the con-

tainers as the same pass under the discharge nozzle or spout.

Still another object of the present invention is to provide a novel power drive for the various mechanisms of the device readily controllable for intermittent operation thereof by the operator at the machine, the said intermittent movement of such control mechanisms being effected by way of a one-half revolution clutch of novel construction which is positive in its action to control with a high degree of exactitude the operation of these control mechanisms.

The invention still further includes as an object the provision of a novel control mechanism for the ejector and folding mechanisms properly synchronized in respect to the operation of the other mechanisms of the device to successively eject the containers from the feeding line into the environment of the operator and to fold the panel of an inner liner for the container. The ejecting mechanism is of such form and construction as to provide positioning means for the containers disposed upon the in-feed conveyor and is of such construction as to be replaceable by similar devices, varying in size, however, to accommodate cartons of various sizes and shapes.

Other objects, features, capabilities and advantages are comprehended by the invention, as will later appear and as are inherently possessed thereby.

Referring to the drawings:

Figure 1 is a view in front elevation of a device made in accordance with the present invention and viewed substantially in the direction represented by the arrows 1—1 as shown in Figure 2 of the drawings;

Figure 2 is a fragmentary top plan view of the device shown in Figure 1 of the drawings, with parts cut away to disclose elements thereof more in detail;

Figure 3 is a fragmentary detached top plan view of a part of the ejecting and closing mechanisms;

Figure 4 is a fragmentary view partly in section and partly in plan of the nozzle mounting which permits angular displacement thereof during the feeding cycle;

Figure 5 is a fragmentary view in end elevation of the device taken in the direction represented by the arrows 5—5 of Figure 2 of the drawings, and showing certain of the parts in section to disclose the construction thereof more in detail;

Figure 6 is a fragmentary view in rear eleva-

tion of the device taken in the direction of the arrows 6—6 of Figure 2 of the drawings;

Figure 7 is a fragmentary view in vertical cross section taken in the plane substantially represented by line 7—7 of Figure 9 of the drawings;

Figure 8 is a fragmentary view partly in plan and partly in section of certain control structure, and taken in the plane substantially represented by line 8—8 of Figure 7 of the drawings;

Figure 9 is a fragmentary view partly in elevation and partly in section taken in the planes substantially represented by line 9—9 of Figure 7 of the drawings;

Figure 10 is a detached fragmentary view in elevation of the one-half revolution clutch and its control mechanism;

Figure 11 is an exploded view in perspective of one of the clutch elements of the one-half revolution clutch and the control elements therefor;

Figures 12 and 13 are fragmentary views in perspective of one of the control elements and one of the clutch parts, respectively, of the one-half revolution clutch;

Figure 14 is an end view of one of the clutch elements of the one-half revolution clutch;

Figure 15 is a fragmentary view in side elevation of the clutch member shown in Figure 14 of the drawings;

Figure 16 is a fragmentary diagrammatic view of the in-feed conveyor and the stop and ejector mechanism associated therewith, disclosing the position of the successively arranged containers;

Figure 17 is a fragmentary diagrammatic view of the elements shown in Figure 16 of the drawings, but disclosing the stop and ejector mechanism in another position in respect to the containers;

Figure 18 is a fragmentary diagrammatic view similar to Figures 16 and 17, but disclosing the stop and ejector mechanism in still another position with respect to the containers;

Figure 19 is a fragmentary view partly in elevation and partly in section of the elements shown in Figures 16, 17 and 18 in their relative position with respect to one another, and in addition the mechanism for partially folding the panel of a liner for the container and its position with respect to said other elements; and

Figure 20 is a fragmentary view partly in elevation and partly in section of the elements shown in Figure 19 with the exception of the filling spout, but showing the relative positions thereof at the time of discharge of the filled container from the in-feed conveyor into a position in proximity to the operator.

Referring now more in detail to the drawings, a device made in accordance with the present invention and selected to illustrate the same is shown as comprising a frame structure, generally referred to as 2, supported upon the foundation or floor 4 and adapted to provide a mounting for the various instrumentalities and mechanisms in proper relation to one another. Since this frame is of somewhat conventional construction embodying such elements as the upright elements 6 and cross pieces 8, as well as various brackets and supports, such as 10, further reference to the detailed structure of this frame will not be made except insofar as is necessary in conjunction with the further detailed explanation of the various elements of the mechanisms to be hereafter more fully described.

The device herein contemplated is of the automatic type embodying certain instrumentalities for successively and progressively filling and

ejecting filled containers, such as fibrous cartons and the like, and at the same time folding the front panel of a liner of fluid-proof material disposed within the said container so as to facilitate the further folding of said liner and closing of the carton as a final step in the completion of the finished packaged goods.

The machine embodies in its construction an in-feed conveyor, generally referred to as 12, which, as will be explained hereinafter, is continuously driven for successively moving opened cartons into a position beneath the discharge nozzle 14 of a metering and delivery mechanism, generally referred to as 16, which successively delivers measured quantities of fluid material to said containers. The containers are normally positioned by a stop and ejector mechanism, generally referred to as 18, which operates in proper synchronized relation to the fluid delivering means for successively discharging the filled cartons onto a table or platform 20 laterally disposed with respect to the in-feed conveyor 12. Closely associated with the stop and ejector mechanism is a slider mechanism, generally referred to as 24, which operates at substantially the time the filled containers are discharged onto the platform 20 to fold inwardly over the material within the container the front flap of the liner disposed within the container. An operator standing opposite the discharge mechanism 18 completes the folding and closing operations on the discharged container while the next succeeding container is being filled by the spout 14 after which the said carton is discharged from the machine through the medium of a discharge conveyor, generally referred to as 22.

In conjunction with the various mechanisms above referred to in a general way is a control mechanism, generally referred to as 26, for operating the various elements of the device in proper sequence and which is under control at all times of the operator at the front of the machine.

The various elements of the machine are operated through the medium of a prime mover 28 in the form of an electric motor mounted upon the platform 30 supported by the frame 2 and which, through the driving pulley 32 and belts 33 operates the pulley 34 mounted on a shaft 36 journaled in the spaced bearings, such as 38, secured to the frame 2, and upon which shaft 36 is mounted a sprocket 40 which, through the chain 42, operates a sprocket 44 mounted upon one end of the shaft 46. Shaft 46 is journaled adjacent its ends in the bearings 48 and 50 secured to frame 2 and disposed adjacent the top of the said frame structure 2. Mounted upon the shaft 46 are the sprocket wheels 54 and 56 which drive the conveyor chains 58 and 60, respectively, which pass over the same and which serve as the in-feed conveyor for the cartons to be filled by the machine. These chains 58 and 60 pass over sprocket pulleys, such as 62, disposed in opposed relation to the sprocket pulleys 54 and 56 at the opposite end of the machine and which are mounted upon a shaft 64 journaled in fixed bearings 66 secured to the frame structure 2 adjacent its upper part to dispose said chains at substantially the level of the table or platform for moving the cartons successively and progressively into abutment with the stop and ejector mechanism 18 and beneath the spout 14, as will be explained more in detail as the description proceeds.

The discharge conveyor generally referred to

as 22 comprises a belt pulley 68 mounted upon shaft 46 and over the periphery of which passes the belt 70 which extends longitudinally of the machine and passes over the belt pulley 72 mounted upon shaft 74 which is journaled in the bearings 76 secured to the frame structure 2 adjacent the top thereof to dispose the said pulley 72 in opposed relation to the pulley 68. As a somewhat conventional conveyor structure, the guide elements 78 and 80 may be provided on opposite sides of the in-feed conveyor, the said guides 78 having as a supplement thereto an adjustable guide member 82 which may be moved laterally with respect to the conveyor chains 58 and 60. Furthermore, the discharge conveyor 22 may be formed with similar guide members, such as 84 and 86, on opposite sides of the belt 70 to properly guide the filled cartons as the same are discharged from the machine.

The control mechanism 26 is enclosed within a housing 88 mounted upon the frame structure 2 by way of the channel members 90 and 92 and embodies in part a shaft 94 mounted in the housing 96 through the medium of the spaced anti-friction bearings 98 and 100 and which said housing is secured in an opening in one of the front plates of the housing 88 by the peripheral flange 102 and the stud bolts 104. This shaft extends through the outer end of the housing 96 and has mounted thereon the sprocket wheel 106 which is continuously driven through the medium of the chain 108 which passes around and is driven by the sprocket 110 mounted upon the transverse power shaft 46. The housing 96 is made substantially fluid-tight at its inner end by way of the cover plate 112 secured thereto as by means of the stud bolts 114 to prevent loss of lubricant which is retained within the housing 88 for the various control elements to be hereinafter described. Adjacent the outer end of the shaft 94 is a gasket or washer 116 of leather, or other flexible material, to prevent the ingress of dirt and other foreign material into the bearings for said shaft.

The power drive through the shaft 94 for the control mechanism is effected by way of a one-half revolution clutch, generally designated as 118, the details of which will be hereinafter more fully described, but which includes a clutch member 120 fixed to the inner end of shaft 94 and a clutch member 122 fixed to the inner end of the shaft 124 in substantial alignment with and driven by the shaft 94 through the clutch 118. The shaft 124 adjacent its inner end is mounted for rotation in anti-friction bearing 126 supported within bearing hub 128 of a partition member 130 extending transversely of the housing 88 and formed integral with the opposed walls thereof. The shaft 124 has its outer end journaled in the anti-friction bearing 132 mounted in the bearing hub 134 of the rear partition wall 136, the said shaft being positioned by means of the adjusting lock nut 138 threaded to the extreme end of said shaft 124. The entire journal bearing at this end of the shaft is suitably enclosed by the closure cap 140 secured to the end wall 136 as by means of the stud bolts 142 or the like.

Mounted upon the shaft 124 are the cam members 144, 146 and 148 constituting control elements for certain of the mechanisms, and the structure of which will be hereinafter more fully described.

The control mechanism further embodies a shaft 150 extending substantially parallel to the

shafts 94 and 124 and which is rotatably mounted through the medium of the spaced bushings 152 and 154 in the sleeve 156 journaled through the medium of a bushing 158 in the bearing hub 160 formed in the front plate of the housing 88. The shaft 150 and sleeve 156 are protected against excessive wear by virtue of the retainers 162 and 164 suitably mounted, as shown in Figure 7, in the sleeve 156 and the bearing hub 160, respectively, to prevent the ingress of dirt or other foreign substances into the environment of said shaft and sleeve. The assembly at the inner end of the sleeve 156 is positioned by means of the collar 166 secured to the shaft 150 by the pin 168. Shaft 150 transmits rotary movement thereof to a lever 170 connected to the shaft at its outer end and which lever operates the valve of the material feeding means, as will be hereinafter more fully set forth.

Keyed to the rotatable sleeve 156 at its outer end is a lever 172 pivotally secured at its opposite end to a connecting rod 174 which in turn is connected to the foot pedal as at 176 whereby control movements from the pedal are transmitted to said rotating sleeve 156 to cause angular displacement of the clutch control element 178 which is secured as by means of welding 180 or the like to the inner end of said sleeve and which projects toward and serves as a means of controlling the clutch 118.

The inner end of shaft 150 is journaled in a bushing 182, which in turn is mounted in the bearing hub 184 provided in the partition member 130. The bushing 182 is retained in operative position with the bearing hub 184 by means of the collar 186 secured to the shaft by the pin 188. The shaft 150 extends through the bearing hub 184 and has mounted on its inner end the hub 190 of the cam follower arm 192 which is provided at its other end with the transverse stub shaft 194 upon which is mounted a cam roller 196 operating within a cam groove 198 of the cam 144, whereby movement of shaft 150 takes place in proper coordinated relation to other elements of the control mechanism to operate lever 170, all as will be hereinafter more fully disclosed. Washer 200 is provided between the hub 190 and the bearing hub 184 to properly adjust the shaft 150 and to take up wear between hub 190 and the bearing hub 184.

The construction of the one-half revolution clutch is more readily comprehended by reference to Figures 7 and 9 to 15 inclusive. The clutch member 120 is formed on its face with a plurality of teeth 202 adapted to receive the teeth 204 and 206 of the pawl clutch elements 208 and 210, respectively, which are carried by the clutch member 122. Each of these pawl clutch elements is of similar construction and is mounted for movement within suitable openings or recesses provided in clutch member 122 and is normally urged outwardly with respect to said clutch member 122 through the medium of the coil springs 212 whereby the said pawls, under the impulse of springs 212, will engage the teeth 202 of clutch member 120.

Since the present invention contemplates the intermittent operation of the various mechanisms controlled by cams 144, 146 and 148, and then only under direct control of the operator through the medium of the pedal 176, novel means is provided for normally holding the pawl clutch elements 208 and 210 out of operative engagement with the teeth of clutch member 120, the said 75 interlocking of the pawl clutch elements with the

teeth of clutch member 120 being effected only as desired and upon operation of the foot pedal 176 by the operator. One of such control elements has been referred to as 178, and since intermittent half revolutions of the shaft 124 are desired, as will later appear, a second control element 214 is provided in opposed relation to control element 178 and which is mounted by way of the bracket 216 to the housing 88.

The movement of the control element 178, as hereinbefore described, takes place upon angular movement of the sleeve 156. The pawl clutch elements are of similar construction, and while the control elements 178 and 214 are of somewhat similar construction, nevertheless there are some differences as will appear as the description proceeds. The control element 178 is formed with a cut-out formed in part by the stop shoulder 218 and in part by the cam surface 220. When the control element 178 is in its normal position, the same is in the way of the pawl clutch element 208 with its under curved surface corresponding essentially to the surface 222 of the control element 214 bearing over the surface 224, and with its cam surface 220 in engagement with the cam surface 226 of the pawl clutch element 208. Abutment stop 218 is in engagement with the stop shoulder 228 of the pawl clutch element 208 when the clutch is disengaged and control element 178 is in its normal position. When these elements are in cooperative relation, the cooperating cam surfaces 220 and 226 cause an inward movement of the pawl clutch element 208 against the compression of spring 212 to maintain the tooth 204 out of engagement with the teeth 202 of the clutch member 120. The control element 214, while similar in construction to the control element 178, does not have a stop shoulder corresponding to stop 218 of control element 178. Thus, while the pawl clutch element 210 is moved by the control element 214 simultaneously with movement of pawl clutch element 208 by the control element 178, there is no positive interlock between these elements and control of the clutch is through the control element 178.

When it is desired to transmit motion to shaft 124, the clutch element 178 is moved through the operation of sleeve 156 to disengage stop shoulder 218 from the stop shoulder 228 and to disengage cam surface 220 from cam surface 226, thus permitting the pawl clutch element 208, under the impulse of spring 212, to engage a tooth 202 of clutch member 120 to couple shaft 124 with shaft 94. Simultaneously with the movement of pawl clutch element 208, pawl clutch element 210 rides over the cam surface 220 of the control element 214, and under the impulse of spring 212 likewise engages a tooth 202 of clutch member 120.

In order to assure proper and smooth operation of the clutch mechanism, the opposed faces 222 of the said control elements 178 and 214 are curved as disclosed and cooperates with the curved surfaces, such as 224 and 230, of the pawl clutch elements 208 and 210. The cooperating surfaces 220 and 226 of the clutch control elements and the pawl clutch elements are developed as screw surfaces to facilitate proper operation of the said pawl clutch elements into and out of engagement with the teeth of clutch member 120. The present clutch mechanism also embodies a particular form of tooth structure for both the clutch member 120 and the pawl clutch elements 208 and 210, including the cooperative radial faces as at 232, which assures a positive drive in both directions, thus preventing over-riding of

the clutch member 122 in respect to clutch member 120. Furthermore, the clutch control element 214 is provided with stop 234 which, when in cooperative relation with either of the pawl clutch elements 208 or 210, prevents reverse rotation of the clutch member 122 which might otherwise take place in that the springs 212 have a tendency to cause this reverse rotation by their application of an axial force to the pawl clutch elements.

In order to maintain clutch control element 178 in cooperative association with either of the pawl clutch elements 208 or 210, the said clutch control element extends from the sleeve 156 through a U-shaped bracket 236 connected to a wall of the housing 88, the said control element 178 being urged forwardly into cooperative relation with either of the pawl clutch elements 208 or 210 by a coil spring 238 embracing the positioning elements 240 and 242 at its opposed ends which are connected to the control element 178 and the wall 244 of housing 88, respectively, and abutting said control element 178 and wall 244.

Movement of the foot pedal 176 through the medium of the connecting rod 174 and lever 172 causes angular displacement of sleeve 156 which is transmitted to the control element 178 which, against the movement of coil spring 238, becomes disengaged from either of the clutch elements 208 or 210. Upon release of the foot pedal 176, however, the control element 178 is returned under the impulse of spring 238 into position to intercept either of the pawl clutch elements 208 or 210.

The metering and delivery mechanism 16 includes a double-acting metering cylinder 246 mounted as indicated upon the bracket 10 of the frame structure 2 and which has a free floating piston for measuring and delivering through the pipe 248 quantities of fluid material to the discharge nozzle 14, the device in the present instance being designed particularly for delivering lard in fluid condition to the containers or cartons successively delivered into position beneath the end of the nozzle or spout 14 for receiving charges of said lard, although it is contemplated that the machine may be used for packaging other materials if seen fit to do so.

This fluid measuring device is controlled by a four-way valve 250, which in turn is controlled through a universal linkage 252 connected to the valve stem 251 at one end by the operating lever 253 and to the end of the valve lever 170, whereby the operation of the fluid measuring device is effected in proper sequence with the other operating mechanisms of the device, it being understood, of course, in accordance with the previous description, that the operation of lever 170 is in accordance with the angular displacement of shaft 150 which takes place in accordance with the movement of cam 144 operating upon the cam roller 195.

The spout or nozzle 14, as previously alluded to, has angular displacement as shown particularly in Figure 5 of the drawings, and in order to accommodate such movement the said spout or nozzle, as more particularly shown in Figure 4 of the drawings, is provided with a hub 254 embracing the end of the pipe 256 which is connected to the pipe conduit 248 through the T-connection 258. This pipe 256 is mounted in the bearing 260 secured to the top of the frame structure 2, and not only positions the nozzle or spout, 14, but likewise the anti-drip mechanism 262 to be later described. The end of the pipe 256 is closed as

at 264 and is provided with a threaded extension 266 adapted to extend through an end wall 268 of the nozzle hub 254 and through the medium of an interposed washer 270 and a lock nut 272 is adapted to position said hub with respect to the pipe or conduit 258. Closure cap 274 threadedly engaging the hub 254 at one end is provided to enclose the end of this assembly to prevent leakage and to provide against the ingress of any dirt or foreign substances therein. The opposite end of this assembly is likewise provided with a closure cap 276 threadedly engaging an opposed end of hub 254 and embracing a gasket or washer 278 to effect a tight connection at this point. The discharge conduit 256 about which the spout 14 rotates is provided with a plurality of apertures 280 communicating with chamber 282 provided in the hub 254 and which communicates with the duct of said spout to provide for discharge of fluid material through the spout irrespective of its angular position.

Angular movement of the spout is effected through a lever arm 284 constituting an extension of the hub 254 and which, through a link 286, is connected to the upper end of rod 288 extending downwardly through the housing 88 and journaled at one end in the bearing gland 290. This connecting rod 288 is secured to the upper end of a saddle 292 straddling the shaft 124 and which is provided with a cross-head 294 provided with a cam roller 296 operable within the cam groove 298 of the cam 146. This cam 146, through the medium of the cam roller 296 and saddle 292, causes reciprocation of the connecting rod 288 to impart angular movement to the spout 14 in predetermined sequence in the fluid delivery cycle, the spout 14 being in its lowermost position when delivery of fluid material takes place, and the upward movement being effected after delivery of the material to provide clearance for movement of the filled container into ejecting position and movement of an empty container into filling position.

Movement of the ejector and slider mechanisms is secured by a lever 300 mounted on the upper end of shaft 302 extending downwardly through the top plate 304 and which is journaled in the bushings 306 and 308 mounted in the bearing 310 secured to the adjacent wall of the closure or container 88. This shaft 302 has a follower arm 312 connected adjacent its lower end, which carries a shaft 314 upon which is mounted a cam roller 316 adapted to cooperate with a cam groove 318 formed in the periphery of the cam 148. Through the medium of the cam 148 the shaft 302 is rotated in predetermined sequence to the operation of the other mechanisms of the device to move the lever 300 between the positions indicated in full and dotted lines in Figure 2 of the drawings.

In order to minimize the drip of fluid material from the end of the filling nozzle at the end of a filling cycle, the anti-drip device 262 is provided. This anti-drip device is constituted by a cylinder 320 connected to the T-fitting 258 and therefore in direct communication with the discharge conduits 248 and 256. This cylinder is provided with a piston 322 spring-pressed upwardly by means of the coil spring 324 and the operation of which piston is effected by one leg 326 of a bell crank lever 328 which is pivoted as at 330 to the closure or container structure 88. The arm 326 has its free end extending through a slot 332 of the cylinder 320 and engages in the slot or recess 334 of piston 322 to

5 impart reciprocating movement to the piston 322 when the same is operated. The bell crank lever 328 is further provided with an upstanding leg 336 in the way of an extension 338 for the lever 5 300, so that when the lever moves into its dotted line position as shown in Figure 2 of the drawings, the bell crank lever 328 is given a quick movement counter-clockwise, as viewed in Figure 5 of the drawings, to move piston 322 downwardly, 10 thus creating a suction drawing fluid from the end of the nozzle back into the discharge system to minimize dripping at the end of the filling cycle. This fluid material sucked back into the system by operation of the piston 322 of course 15 is put back into the system at the beginning of the next filling cycle through the action of the spring 324.

The combined stop and ejector mechanism 18 is in the form of a movable stop 340 having a leg 342 extending transversely of the conveyor 12 and another leg 344 spaced longitudinally with respect to the leg 342 and extending in normal relation to a longitudinally disposed leg 346. This movable stop member is adjustably secured as by means of the wing nut and bolt assemblies, generally referred to as 348, to the cross-head assembly 350 secured at the ends of the parallelly disposed rods 352 and 354 mounted for sliding movement in the fixed guides 356 and 358. Immediately above, but independently of the movable stop 340 is a sliding blade 360 which, through the medium of the wing nut and bolt assemblies 362, is adjustably secured to the cross-head 364 mounted at the end of the parallelly disposed rods 366 and 368, likewise slidably mounted in the fixed guides 356 and 358.

Linear movement of the stop 340 transversely in respect to the conveyor 12 is effected by the rods 352 and 354 by way of a link 370 pivotally connected at one end as at 372 to the end of lever 300 and pivotally connected at its other end as at 374 to a bracket 376 secured to said rods 352 and 354. Movement of the sliding blade 360 transversely with respect to the conveyor 12 and independently of the moving stop 340 is imparted through the rods 366 and 368 by way of the lever 378 which is pivotally connected as at 380 to the cross-head 364, this movement of lever 378 being imparted by a link 382 connected intermediate the ends of lever 378 and having a pivotal connection with the bracket 376. The other end of lever 378, as at 384, is pivotally connected to a link 386 which in turn is pivoted as at 388 to the bracket 390 extending laterally of the housing 88.

Referring more specifically to Figures 16 to 20 inclusive, wherein certain of the parts immediately hereinabove described are shown somewhat diagrammatically, it will be noted that the stop member 340 has various operative positions 60 transversely of the in-feed conveyor 12. As is well understood, one form of container which may be used in conjunction with the present mechanism takes the form of a cardboard carton 392 having a top closure flap 394 and in which is disposed a liner 396 of waterproof material formed with an upper open end, the side walls forming the liner extending above the upper open end of the carton 392, all as clearly shown in Figures 19 and 20 of the drawings. These cartons with the liner disposed therein are fed onto the conveyor 12 and are carried into a position such as shown in Figure 16 whereby the foremost carton is disposed directly beneath the open end of the spout 14. When this foremost

carton is in the position disclosed in Figure 16, the end of the spout has been lowered into the interior of the liner to deposit a measured quantity of the fluid in the carton. While the conveyor 12 is continuously operated, nevertheless the foremost carton is temporarily arrested in its movement on the conveyor by the stop member 340 which, when the foremost carton is moved into receiving position, has its leg 342 disposed in respect to the conveyor 12, as shown in Figure 16, so as to act as a stop member for said foremost carton.

After a dispensing operation has taken place, the nozzle 14 is angularly displaced in accordance with the previous description, and the movement of the rods 352 and 354 is such as to retract the stop member 340 from its engaging relation with the end of the carton being filled, all as disclosed in Figure 17 of the drawings, whereby the foremost container which has then been filled with fluid material is picked up by the conveyor 12 and moved into engagement with the stop leg 344 of said stop member 340. Simultaneously with the movement of this foremost carton, the next adjacent carton to the rear thereof moves into filling position directly beneath the discharge end of the spout 14, at which time the control mechanism is operated to lower the spout to discharge material into said carton. Simultaneously with the filling of the next succeeding carton, all in accordance with the above disclosure, the rods 352 and 354 are moved through the medium of lever 300 and link 370 to engage the first filled carton above described to move the same laterally from the conveyor chains 58 and 60 and onto the table or top 20, as shown in Figure 18 of the drawings. During this movement of stop member 340, the leg 342 thereof, while moving laterally with respect to the next immediate carton being filled, nevertheless is of such a length that it still provides a stop member for said carton.

During movement of the stop member 340 for ejecting the filled cartons, the sliding blade 360 is moved transversely of the conveyor 12 through the medium of the rods 365 and 368 by way of the linkage hereinabove described, into engaging relation with the front panel 398 of the liner, all as disclosed in Figure 20 of the drawings, to fold said panel downwardly into substantially horizontal engaging relation with the material contained within the carton, and simultaneously effecting a fold of the end panels, such as 400, which facilitates further folding of the liner and closing of the top flap 394 of the carton. Upon ejection of the filled cartons onto the table 20 with the front panel of the liner folded as described, the operator standing in front of table 20 can then complete the folding of the liner and the closing of the flap of the cartons as the same are successively ejected from the in-feed conveyor, after which the same may be placed in contact with the belt 70 of the take-away conveyor for discharge of the same from the machine.

As hereinbefore alluded to, the operation of the device in accordance with the immediately above description takes place intermittently when the operator presses upon the pedal 176. This initiates operation of the one-half revolution clutch 118, causing a one-half revolution of shaft 124, which operation affects the other control elements to bring about certain operations of the various instrumentalities in proper sequence to produce the results hereinbefore described. For

example, upon operation of the shaft 124, cam 144 causes rotation of shaft 150 through the medium of the cam rod 192, which rotation of shaft 150 causes movement of lever 170. This lever, through the universal linkage 252, operates the conventional four-way valve 250 to operate the measuring device 16 to deliver through discharge pipe 248 a measured quantity of fluid material through the discharge nozzle 14, as hereinbefore described. This same rotation of shaft 124 operates cam 146, which, through the medium of roller 296, causes reciprocation of rod 288, which raises and lowers the spout 14. This same movement of shaft 124 further causes rotation of cam 148, which operates through roller 316 to rotate shaft 302, which in turn causes operation of the lever 300 which, while having the primary function of operating the stop and ejector mechanism, as well as the mechanism for partially folding the liners, has, in addition, the secondary function of moving the bell crank lever 328 to operate the anti-drip mechanism at the end of a filling cycle.

As is apparent from the above description, the shaft 124 is stationary in a definitely fixed position at the end of one-half revolution. Inasmuch as the operator releases the pedal 176 after each operation, clutch element 118 has been released, so that at the end of the cycle of operation of shaft 124, the clutch 118 is automatically disengaged. The shaft 94, however, driven through the sprocket 106, continues to rotate during the operation of the machine. It is to be noted that the cam 148 which operates the lever 300, and cam 146 which operates the reciprocating rod 288, are designed to move these parts through a complete cycle for each one-half revolution of the shaft 124. The cam 144, however, which operates the valve 250, is designed to move the lever 170 through only one-half of its cycle of operation for each one-half revolution of the shaft 124. The reason for this difference in cam design is that the valve 250 brings about the delivery of a full charge of fluid material from the metering cylinder 246 at each one-half cycle of the valve movement. For each predetermined volume of fluid delivered by the metering cylinder 246, however, the filling spout 14 and carton control mechanisms 18 and 24 must each operate through a full cycle.

While I have herein described and upon the drawings shown an illustrative embodiment of the invention, it is to be understood that the invention is not limited thereto but may comprehend other constructions, arrangements of parts, details and features without departing from the spirit of the invention.

I claim:

1. In a machine for filling cartons and the like having inner liners, the combination of a continuously operable conveyor for feeding cartons and the like into the machine, a material delivery spout, control means associated with said conveyor and spout for positioning successively presented cartons and the like for receiving material discharged from said spout and for successively ejecting said filled cartons and the like laterally of said conveyor, and means driven from and associated with said control means for folding the front panel of the inner liner of said cartons and the like during the ejecting cycle.
2. In a machine for filling cartons and the like having inner liners, the combination of a continuously operable conveyor for feeding cartons and the like into the machine, a material

delivery spout, means having reciprocal movement transversely with respect to said conveyor for positioning successively presented cartons and the like for receiving material discharged from said spout and for successively ejecting said filled cartons and the like laterally of said conveyor, and means having reciprocal movement transversely with respect to said conveyor and associated with said first named means for folding the front panel of the inner liner of said cartons and the like during the ejecting cycle.

3. In a machine for filling cartons and the like having inner liners, the combination of a continuously operable conveyor for feeding cartons into the machine, material discharge means including a material delivery spout, carton positioning means including a combined stop and ejector means mounted for reciprocal movement transversely with respect to said conveyor for holding successively presented cartons and the like in material receiving and ejecting positions, means mounted for reciprocal movement transversely with respect to said conveyor and associated with said positioning means for folding the front panel of the inner liner of said cartons and the like during the ejecting cycle, and cam controlled mechanism for operating said means.

4. In a machine for filling cartons and the like having inner liners, the combination of a continuously operable conveyor for feeding cartons into the machine, material discharge means including a material delivery spout, carton positioning means including a combined stop and ejector means mounted for reciprocal movement transversely with respect to said conveyor for holding successively presented cartons and the like in material receiving and ejecting positions, means mounted for reciprocal movement transversely with respect to said conveyor and associated with said positioning means for folding the front panel of the inner liner of said cartons and the like during the ejecting cycle, and cam controlled lever and link mechanism for operating said control and folding means in predetermined sequence.

5. In a machine for filling cartons and the like having inner liners, the combination of a continuously operable conveyor for feeding cartons into the machine, a material delivery spout mounted for reciprocal pivotal movement, carton positioning means including a combined stop and ejector means mounted for reciprocal movement transversely with respect to said conveyor for holding successively presented cartons and the like in material receiving and ejecting positions, means mounted for reciprocal movement transversely with respect to said conveyor and associated with said positioning means for folding the front panel of the inner liner of said cartons and the like during the ejecting cycle, and mechanism for operating said positioning and folding means and for reciprocating said spout during a material feeding cycle.

6. In a machine for filling cartons and the like having inner liners, the combination of a continuously operable conveyor for feeding cartons into the machine, material discharge means including a material delivery spout mounted for reciprocal pivotal movement, anti-drip mechanism associated with said material discharge means, carton positioning means including a combined stop and ejector means mounted for reciprocal movement transversely with respect to said conveyor for holding successively presented cartons and the like in material receiving and

ejecting positions, means mounted for reciprocal movement transversely with respect to said conveyor and associated with said positioning means for folding the front panel of the inner liner of said cartons and the like during the ejecting cycle, and means for operating said anti-drip mechanism, carton positioning and folding means and for reciprocating said material delivery spout in predetermined sequence.

10 7. In a machine for filling cartons and the like having inner liners, the combination of a continuously operable conveyor for feeding cartons into the machine, material discharge means including a material delivery spout mounted for reciprocal pivotal movement, anti-drip mechanism associated with said material discharge means, carton positioning means including a combined stop and ejector means mounted for reciprocal movement transversely with respect to said conveyor for holding successively presented cartons and the like in material receiving and ejecting positions, means mounted for reciprocal movement transversely with respect to said conveyor and associated with said positioning means for folding the front panel of the inner liner of said cartons and the like during the ejecting cycle, power-driven control mechanism, means operated by said control mechanism for operating said carton positioning and folding means, means operated by said control mechanism for reciprocating said material delivery spout, and means operated by said control means for operating said carton positioning and folding means and said anti-drip mechanism.

15 8. In a machine for filling cartons and the like having inner liners, the combination of a source of power, a continuously operable conveyor for feeding cartons and the like into the machine, control means operable by said source of power, material delivery means including a movable spout controlled by said control means through which measured quantities of material may be delivered to cartons and the like disposed in material receiving position with respect to said spout, carton positioning means operated by said control means for holding successively presented cartons and the like in position for receiving said material and for successively ejecting said filled cartons and the like laterally of said conveyor, and means operated simultaneously with and by said positioning means for folding the front panel of the inner liner of said cartons and the like during the ejecting cycle.

20 9. In a machine for filling cartons and the like having inner liners, the combination of a source of power, a continuously operable conveyor for feeding cartons into the machine, manually initiated control means operable by said source of power, material delivery means including a movable spout controlled by said control means through which measured quantities of material may be delivered to cartons or the like disposed in material receiving position with respect to said spout, carton positioning means operated by said control means for holding successively presented cartons and the like in position for receiving said material and for successively ejecting said filled receptacles laterally of said conveyor, anti-drip mechanism operated by said control means at the end of a material filling cycle, and means operated by said positioning means for folding the front panel of the inner liner of said cartons and the like during the ejecting cycle.

25 10. In a machine for filling cartons and the like having inner liners, the combination of a

source of power, a continuously operable conveyor for feeding cartons and the like into the machine, material delivery means including a movable spout through which measured quantities of material may be delivered to cartons or the like disposed in material receiving position with respect to said spout, carton positioning means for holding successively presented cartons and the like in position for receiving said material and for successively ejecting said filled cartons and the like laterally of said conveyor, means associated with and driven from said carton positioning means for folding the front panel of the inner liner of said cartons and the like during the ejecting cycle, and control means for operating said material delivery, carton positioning and folding means in predetermined sequence, said control means comprising a continuously operable driving shaft driven by said source of power, a shaft driven by said driving shaft, a manually operable clutch for connecting said shafts, and cam mechanism operated by said driven shaft for operating said material delivery, carton positioning and folding means.

11. A machine for filling a container having a flap to be folded inwardly to close the package comprising a nozzle to deliver material to a container, means to supply material to the nozzle

and means to deliver containers to a position under the nozzle, ejector means reciprocating substantially horizontally to remove the containers from under the nozzle after they have been filled, and a folding means reciprocable with said ejector and driven therefrom to project past the ejector to fold the flap into the container after a charge has been placed therein and acting simultaneously with the ejector to fold the flap

10 while the container is being ejected.

12. A machine for filling a container having a flap to be folded inwardly to close the package comprising a nozzle to deliver material to a container, means to supply material to the nozzle and means to deliver containers to a position under the nozzle, ejector means reciprocating substantially horizontally to remove the containers from under the nozzle after they have been filled, a folding means reciprocable with said ejector to project past the ejector to fold the flap into the container after a charge has been placed therein and acting simultaneously with the ejector to fold the flap while the container is being ejected, and means to drive said folding means in timed relation to the movement of the ejector.

CHARLES T. WALTER.
